(57) **CLAIM**

The ornamental design for a portion of frame for respiratory mask, as shown.

DESCRIPTION

FIG. 1 is a front perspective view of a portion of a frame for a respiratory mask according to our design;

FIG. 2 is a front view thereof; and,

FIG. 3 is a bottom view thereof.

The dashed lines shown in FIGS. 1–3 disclose unclaimed subject matter, are for environmental purposes only, and thus form no part of the claimed design.
